Specification for Design.

Patented Mar. 16, 1920.

Application filed March 2, 1918. Serial No. 220,058. Term of patent 7 years.

To all whom it may concern:

Be it known that I, HARRY COHN, a citizen of the United States, residing at Brooklyn, in the county of Kings and State of New York, have invented a new, original, and ornamental Design for a Frame for Shades for Electric Lights, of which the following is a specification, reference being had to the accompanying drawing, forming part thereof.

The figure is a perspective view of a frame for shades for electric lights, comprising an

upper annular member having an ornamented surface, a lower annular member having an ornamented surface, the two being held in spaced relation by means of a plurality of supports, the space intermediate the supports being filled with silk or similar material.

I claim:

The ornamental design for a frame for shades for electric lights, as shown and described.

HARRY COHN.
